TUYÈRE FOR STOKERS

William F. Rieger, Salt Lake City, Utah, assignor,
by mesne assignments, to Charles T. S. Parsons,
Salt Lake City, Utah

Application March 1, 1933, Serial No. 659,072

3 Claims. (Cl. 110—45)

My invention relates to stokers and has for its object to provide a new and efficient fire pot, tuyère and means for preventing back smoking of the device.

5 A further object is to provide a fire pot of simplified construction in which the tuyère is set, said tuyère being formed of removable rings set one on the other and each provided with tuyère openings through which the forced draft is introduced to the fuel in the fire pot.

10 A still further object is to provide a tuyère having the top formed integral with the cover of the fire pot and air chamber and having the tuyère circular in form and with the tuyère openings 15 formed between spaced apart rings carried under the main tuyère ring of the cover of the fire pot.

A still further object is to provide a fire pot constructed with the tuyère rings mounted under a curved annular expansion and contraction ring 20 and shield ring of the cover of the pot to provide a fire pot and tuyère which will not crack or break, due to the expansion and contraction thereof from the heats in the furnace.

These objects I accomplish with the device 25 illustrated in the accompanying drawing in which similar numerals and letters of reference indicate like parts throughout the several views and as described in the specification forming a part of this application and pointed out in the appended 30 claims.

In the drawing in which I have shown the best and most preferred manner of building my invention

35 Figure 1 is a side elevation of the fire pot and tuyère assembled.

Figure 2 is a plan view of Figure 1.

Figure 3 is a vertical section of the device.

Figure 4 is a plan view of the upper ring of the tuyère which fits under the curved expansion ring.

40 Figure 5 is a plan view of the lower ring.

In the drawing I have shown the rectangular air chamber and base of the fire pot as A, to which a cover B is secured by bolts 1 being passed down through each reinforced corner of the 45 cover B into flanges 2 formed in the upper corners of the pot A. Centrally into one end of the pot A, I provide the inlet casting 3 into which the feed tube and feed worm fit. Onto the top side of the inlet section 3, I provide a sloping chamber 50 4 in open connection with the interior of the pot and with the inlet opening so that when there is air pressure in the fire pot A there will be air pressure passing through the chamber 4 into the opening 3 and out through a curved outlet pipe 55 5 of the tuyère. This prevents back smoking through the device.

The pipe 5 is carried in the pot A by flanges 6 formed on each side thereof and on the end thereof to fit onto brackets 8 formed within the 60 pot A, and the small tapered end 9 of the pipe

is fit onto the end of the screw and feed pipe. The pipe 5 is tapered outwardly at the same time it is curved upwardly and the top end 7 of the pipe is at right angles to the inlet or feed pipe, and onto the top of the pipe 5 I place the smaller 5 of the two tuyère rings. Then over the top of the smaller ring 10 I place a larger ring 11 and onto the top of this is the curved expansion and cover ring 12 of the cover B of the device.

Each ring 10 and 11 are provided with spaced 10 apart bosses 17 to space the rings apart and leave tuyère openings 13 therebetween. The plane 18 of the surface of rings 10 and 11 between the bosses 17 is sloping to prevent dust and ashes entering the pot B through the openings 13. The 15 top ring 11 is provided with depending lugs 14 to hold the rings concentric. The inner bore 15 of the rings and of the expansion ring is tapered, from the expansion ring down to the smallest bore of the lower ring 11, which is the same diameter as the outer bore of the pipe 5. Angled outwardly from the expansion ring 12 toward each corner of the cover B are flanges or braces 16 to brace the rings in its expansion and contraction 20 tying the ring to the corners of the pot A.

Having thus described my invention I desire 25 to secure by Letters Patent and claim:—

1. In an underfeed stoker, the combination of a casing having its upper end open; a fire pot mounted in said casing and spaced therefrom; a 30 cover mounted on the upper end of said casing and spanning the space between said casing and firepot, said cover having a raised annular portion surrounding the upper portion of said fire pot and overlapping the upper edge thereof, said 35 annular portion being raised above the rest of the cover by an annular vertical wall whereby said annular portion may expand and contract without buckling and cracking the cover.

2. The invention as set forth in claim 1 characterized in that said plate is provided with reinforcing ribs extending radially outward from 40 said raised annular portion.

3. In an underfeed stoker, the combination of a casing having its upper end open, a fire pot 45 mounted in said casing and spaced therefrom; annular tuyère rings carried concentric with and on the top of said pot with tuyère openings between said rings; a cover plate mounted on the upper end of said casing spanning the space between 50 said said casing and said tuyère rings; said plate having a raised annular portion surrounding the upper portion of said fire pot and rings and overlapping the upper edge of the top ring, said 55 annular portion being raised above the rest of the plate by an annular vertical wall whereby said annular portion may extend and contract without buckling and cracking said plate.
